ABSTRACT OF THE DISCLOSURE

A hair dye composition comprising a solvent and a quaternary ammonium salt having the formula

in which R_1 is a lower alkyl having 1-4 carbon atoms and A^- is an anion, and the method of dyeing human hair with this composition.

This application is a continuation-in-part of application Ser. No. 428,867, filed Jan. 28, 1965, which is now U.S. Patent 3,531,502.

The present invention relates to 1-hydroxy-2,4-bis(p-dimethyl-aminophenyl)aminoanthraquinone, to a process for its preparation and to the use of its quaternary ammonium salts in the dyeing of keratinic fibers.

It has been found, according to the present invention, that quaternary ammonium salts of 1-hydroxy-2,4-bis(p-dimethylaminophenyl)aminoanthraquinone are useful dyes for dyeing human hair and other keratinic fibers. The quaternary salts of particular value in this respect are those of the formula:

in which R_1 is a lower alkyl having 1-4 carbon atoms (for instance a methyl, ethyl, propyl or butyl radical); and A^- is an anion, such as a halogen, such as Cl, Br and I or a methylsulphate ion.

Examples of two compounds falling within the scope of the above-indicated Formula I are: methyl-[1-hydroxy-2,4-bis(p-trimethylammonium-phenyl)-aminoanthraquinone] sulphate, that is the compound of Formula I where R_1 is methyl and A^- is methylsulphate, and [1-hydroxy-2,4-bis(p-trimethylammonium-phenyl)-aminoanthraquinone] iodide, that is the compound of Formula I where R_1 is methyl and A^- is iodide.

The quaternary salts of this invention when applied to human hair give attractive grey shades of great intensity

2

for which there is need in the art of hair-dyeing. They also have the advantage that they are very soluble in water over a very wide pH range, the aqueous solutions obtained being, in general, tolerant of all the practical conditions under which hair dyeing is carried out. Moreover, the quaternary salts when applied to hair have a high resistance to sunlight, which is a most valuable property for hair dyes, and they also well withstand the presence of ingredients generally incorporated in dyeing compositions, such as hair penetrating and swelling agents, lustre-producing products and thickening agents.

1 - hydroxy - 2,4-bis(p-dimethylaminophenyl)aminoanthraquinone can be obtained by the reaction of N,N-dimethyl-p-phenylenediamine with purpurin, that is, 1,2,4-trihydroxyanthraquinone. The quaternary salts of 1-hydroxy - 2,4 - bis(p-dimethylaminophenyl)aminoanthraquinone can be obtained by reacting the latter compound with a quaternizing agent such as methyl iodide or methyl sulphate.

20 The invention also relates to a method of dyeing keratinic fibers, more particularly hair, by applying to the fibers a quaternary salt of this invention, allowing sufficient time to elapse for the said compound to exert its dyeing effect and then removing any unwanted excess 25 of the compound from the hair. The quaternary salt is conveniently used in the form of an aqueous solution that is left in contact with the hair for about 15 to 60 minutes at ambient temperature, after which the hair is rinsed and washed.

The dyeing compositions suitable for dyeing keratinic fibers may take the form of solutions, emulsions, gels or creams, containing a quaternary salt of this invention. The dyeing compositions of this invention have a pH value of approximately 3 to 9.

35 The dye compositions of the invention may be used in combination with other dyestuffs which may or may not be quaternary salts of this invention or belong to the family of the antraquinone dyestuffs.

The invention is illustrated by the following examples.

40

EXAMPLE I
Preparation of 1-hydroxy-2,4-bis(p-dimethylamino-phenyl)aminoanthraquinone

45 There is heated for 8 hours at 110° C. a mixture consisting of 264 g. of industrial purpurin, 64 g. of boric acid and 1018 g. of N,N-dimethyl(p-phenylenediamine), whereafter the mixture is diluted with 1.5 liters of alcohol and 3 liters of water. The crude product is thereafter separated and recrystallized from chlorobenzene. The product thus obtained has a melting point of 254-255° C. and the following analysis:

Calculated (percent): C, 73.17; H, 5.69; N, 11.38. Found (percent): C, 73.65-73.37; H, 5.80-5.72; N, 11.56-11.22.

55

EXAMPLE II
Preparation of methyl-[1-hydroxy-2,4-bis(p-trimethylammonium-phenyl)-aminoanthraquinone] sulphate

60 This compound is obtained by the action of 11.4 g. of methyl sulphate on a solution of 20 g. of 1-hydroxy-2,4-bis(p-dimethylaminophenyl)aminoanthraquinone in 200 cc. of benzene. The quaternary ammonium obtained is separated, and it melts with decomposition at 200-203° C.

65

EXAMPLE III
Preparation of [1-hydroxy-2,4-bis(p-trimethylammonium-phenyl)-aminoanthraquinone] iodide

65 This compound is obtained by the action of methyl iodide (2.14 g.) on 1-hydroxy-2,4-(p-dimethylaminophenyl)aminoanthraquinone (3.32 g.). It decomposes at 260° C.

3
EXAMPLE IV

A dyeing solution according to the invention is prepared by mixing:

Methyl - [1 - hydroxy - 2,4 - bis(p - trimethylammonium phenyl)aminoanthraquinone] sulphate, 10 g.
Sodium carbonate, q.s. for pH 7
Water, q.s. for 1000 cc.

This solution is applied to 100% white hair and left in contact therewith for 20 minutes at ambient temperature, whereafter the hair is washed, rinsed and dried.

The coloration thus obtained in the hair is violet-grey.

EXAMPLE V

A dyeing solution according to the invention is prepared by mixing:

[1-hydroxy-2,4-bis(p-trimethylammoniumphenyl)-aminoanthraquinone] iodide, 10 g.
Sodium carbonate, q.s. for pH 7
Water q.s. for 1000 cc.

This solution is applied to 100% white hair and left in contact therewith for 20 minutes at ambient temperature, whereafter the hair is rinsed, shampooed, rinsed again and dried.

The coloration thus obtained in the hair is blue-grey.

EXAMPLE VI

A solution according to the invention is prepared by mixing:

Methyl - [4 - hydroxy - 1 - (β-methylmorpholinium)-ethylaminoanthraquinone] sulphate ----- 1.4
1 - (γ - dimethylaminopropyl) - amino - 2 - amino-4-nitrobenzene monohydrochloride ----- 2.8
Methyl - [1 - hydroxy-2,4-bis(p-trimethylammoniumphenyl)aminoanthraquinone] sulphate ----- 8.5
Methyl - [1,5 - bis(β - methylmorpholinium)ethylaminoanthraquinone] sulphate ----- 8.5
Sodium carbonate, q.s. for pH 8.5.
Water, q.s. for 1000 cc.

When applied to light chestnut-colored hair and left for 15 minutes this mixture imparts a pearly-red tinge to the hair, after washing, rinsing and drying.

EXAMPLE VII

A dyeing solution according to the invention is prepared by mixing:

N-monomethylnitro-p-phenylenediamine ----- 6.5
1 - (γ - dimethylaminopropyl) - amino - 2-amino-4-nitrobenzene monohydrochloride ----- 12
Methyl [1-hydroxy - 2,4 - bis(p-trimethylammoniumphenyl)aminoanthraquinone] sulphate ----- 2 55
Methyl [1,4 - bis(β-methylmorpholinium)ethylaminoanthraquinone] sulphate ----- 6
Sodium carbonate, q.s. for pH 8.5.
Water, q.s. for 1000 cc.

This mixture, when applied to natural light-brown hair comprising 30% of white hair and left for 15 minutes, im-

4

parts to the hair, after washing, rinsing and drying, a light brown color having pearly-golden tinges.

Similar hair dyeing results were obtained using the corresponding quaternary ammonium chloride, bromide, iodide, and methylsulphate salts.

Other illustrative compounds include:

[1-hydroxy-2,4-bis(p-propyl, dimethylammoniumphenyl)aminoanthraquinone] chloride
[1-hydroxy-2,4-bis(p-ethyl, dimethylammoniumphenyl)aminoanthraquinone] bromide and
[1-hydroxy-2,4-bis(p-butyltrimethylammoniumphenyl)aminoanthraquinone] iodide.

What is claimed is:

1. A dye composition suitable for dyeing human hair comprising a solution of a quaternary salt of 1-hydroxy-2,4 - bis(p - dimethyl-aminophenyl)aminoanthraquinone of the formula:
